UNITED STATES PATENT OFFICE.

ARNOLD STUCKI, OF PITTSBURGH, PENNSYLVANIA.

ROLLER SIDE BEARING.

1,096,473.

Specification of Letters Patent. Patented May 12, 1914.

Application filed July 25, 1912. Serial No. 711,456.

To all whom it may concern:

Be it known that I, ARNOLD STUCKI, a resident of Pittsburgh, in the county of Allegheny and State of Pennsylvania, have 5 invented a new and useful Improvement in Roller Side Bearings, of which the following is a specification.

This invention relates to side bearings for railway cars.

The object is to provide a side bearing which is practically frictionless under all service conditions, whether normal or abnormal, and which performs all of the other necessary functions of side bearings, which 15 is efficient and durable in service, and which is very simple in construction and, therefore, inexpensive both as to first cost and as to up-keep.

The invention comprises a side bearing 20 constructed and arranged as hereafter described and claimed.

In the accompanying drawings Figure 1 is a plan view of one form of the bearing; Fig. 2 is in part a side view and in part a 25 vertical longitudinal section thereof; Fig. 3 is in part an end view and in part a vertical cross section thereof; Fig. 4 is a plan view showing a modification; Fig. 5 is in part a side view and in part a vertical longitudinal section therof; and Fig. 6 is a plan view of still another modification.

In the drawings the side bearing is shown adapted for attachment to a straight truck bolster, but it can be readily adapted to a 30 tapering truck bolster.

The bearing comprises a suitable frame or housing 1 having its lower face corresponding to the face of the bolster 2 to which it is attached. This frame or housing is provided with a bottom 3, side walls or barriers 4, end walls or barriers 5, and with suitable ears 6 perforated for the reception of rivets or bolts for securing the same to the bolster. The bottom provides a suitable bearing surface for the roller 8, which bearing surface may be either integral with the bottom, or formed by a separate hardened steel plate 9 secured thereto by rivets 10 or the like. The side and end walls or barriers 40 confine the roller and prevent it from jumping out of the housing under normal operating conditions. Said walls or barriers are, therefore, of very material height, extending fairly close to the top of the roller 8, as shown, and the end walls or barriers have 45 their upper portions substantially vertical so

that the roller cannot roll up out of the same, said end walls forming a stop to limit the travel of the roller in both directions. The side and end walls have broad flat top 60 edges which will form an efficient side bearing even if the roller should be lost in a wreck or for other cause.

To prevent the housing from accumulating dirt and, therefore, clogging the travel 65 of the roller, the walls are preferably of open or skeleton construction, the end walls being provided with large openings 11 extending for the full width of the housing and for a considerable distance upwardly, 70 while the side walls 4 are provided with large openings 12 at the central portion thereof. The result is that the barriers are practically supported upon four corner portions or columns 13, with large openings 75 both at the level of the bearing surface at the ends and sides through which snow, ice, dust or other foreign matter can readily escape so as to prevent clogging the roller. The side walls or barriers are strengthened 80 and stiffened by horizontal ribs or flanges 14 and vertical ribs or flanges 15.

The roller 8 is preferably a plain faced cylindrical roll, as shown, although if desired it may be slightly conical or tapered 85 and the housing curved on an arc to correspond therewith. The bearing surface 9 is, under load, perfectly level from end to end so that the roller can travel thereon without friction and without the necessity of lifting 90 the car body as it rolls toward its ends, as is the case with side bearings in which the bearing surface for the roller is inclined from its center upwardly toward its ends. Consequently, the roller travels very freely, 95 rolling practically without friction and without lifting or lowering its center of gravity, and without being obliged to lift any part of the car body. It, therefore, permits much freer swiveling of the truck 100 underneath the car body than that type of bearing in which the roller, as it moves from the center toward the ends, is compelled to roll up an incline. It is desirable, however, to provide suitable means for returning the roller to central position in the housing when the bolsters separate, in order to be in proper position when the bolsters 105 again come together. On account of the level or horizontal character of the bearing 110 surface 9 the roller will not automatically roll to central position upon separation of

the bolsters. I have, however, provided for this in various ways, the preferred way being by means of plate springs acting against the roller and situated at the bearing surface.

Figs. 1, 2 and 3 show a pair of plate springs 18 each having both ends inclined upwardly, and held in such position that normally they lie slightly above the bearing surface 9. When the roller rolls from its central position toward either end it depresses these springs, placing them under tension, so that as soon as the bolster separates the recoil of the springs causes the roller to roll by gravity to central position, as will be readily apparent. The springs 18 in Figs. 1, 2 and 3 are held in position by providing them centrally with the depressed portions 19 which are clamped between the bottom 3 of the housing and lateral projections 20 on the wearing plate 9. A spacing or filling plate 21 is preferably placed between the bottom 3 of the housing and the wearing plate 9. If desired, the springs 18 and spacing or filler plate 21 can be made integral, or, in other words, a single integral plate can have the spring arms 18 slit therefrom and bent to the form shown so as to project upwardly in the cut-away corner portions of the wearing plate.

Figs. 4 and 5 show a modification wherein a single spring plate 22 is secured to the base 3 of the housing by means of rivets 23 and has portions 18^a slit from the body at each corner and bent upwardly to form the inclined spring arms. In this case the spring arms 18^a also become portions of the bearing surface when depressed by the roller traveling over the same, while in Figs. 1, 2 and 3 the spring arms are merely depressed below the lower surface of the wearing plate 9, and do not contact with the base and, therefore, strictly speaking, do not form a portion of the bearing surface.

Fig. 6 illustrates a modification in which a single spring plate 22^a is employed, having its end portions bent upwardly for the entire width, instead of having portions at the corners slit, as in Fig. 4, and bent upwardly.

In all of the modifications the centering means comprises plate springs forming spring arms lying at each side of the transverse center of the bearing surface, and inclined upwardly toward their ends, in such position that when the roller travels toward either end of the bearing the spring arm or arms on that side of the roller are depressed and placed in tension and serve by their recoil to cause the roller to return by gravity to central position whenever the bolsters separate.

With all forms of the bearing a plain faced roller is free to travel upon a level bearing surface, without friction and with-

out being compelled to either rise or fall as it rolls. Consequently, the roller travels with the swiveling of the truck with the greatest facility, and by reducing friction between the truck and car body, assists the free swiveling of the truck under the car body. All forms provide very simple and easily applied means for returning the roller to central position whenever the bolsters separate.

What I claim is:

1. A side bearing for railway cars, comprising a housing or frame for the lower bolster and having its bottom forming a bearing surface, a roller coöperating with said bearing surface, and members projecting upwardly from the bottom of said housing, said members being inclined downwardly from the ends toward the center thereof when the roller is without load and each thereof being arranged to yield when the roller travels under load along said bearing surface toward one end of the housing and serving to return the roller to central position.

2. A side bearing for railway cars comprising a housing for the lower bolster and provided with side and end retaining walls or barriers and having its bottom forming a bearing surface level from end to end, a roller in said housing free to roll on said bearing surface, and spring members at the bearing surface inclined upwardly from the center toward the ends of the bearing surface and normally projecting above the bearing surface, said spring members acting independently of each other and being arranged to be contacted and placed under tension by the roller and serving to return the roller to central position when the bolsters separate.

3. A side bearing for railway cars comprising a housing for the lower bolster and provided with side and end retaining walls or barriers and having its bottom forming a bearing surface level from end to end, a roller in said housing free to roll on said bearing surface, and a spring plate rigidly secured intermediate its ends to the housing and having end portions inclined upwardly toward the ends of the housing and arranged to be depressed by the roller as it travels toward the ends of the housing and serving to return the roller to central position when the bolsters separate.

4. A side bearing for railway cars comprising a housing for the lower bolster and provided with side and end retaining walls or barriers and having its bottom forming a bearing surface level from end to end, a roller in said housing free to roll on said bearing surface, and separately acting upwardly inclined plate springs normally lying above the bearing surface and each arranged to be depressed independently of the other.

by the roller when it travels toward one end of the housing and serving to return the roller to central position when the bolsters separate.

5. A side bearing for railway cars comprising a housing for the lower bolster and provided with side and end retaining barriers and having a bottom forming a bearing surface level from end to end, a roller in said housing free to roll on said bearing surface, and a spring member secured between said wearing plate and the bottom of the housing and having upwardly inclined end portions normally lying above the surface of said wearing plate.

10. In testimony whereof, I have hereunto set my hand.

15. A side bearing for railway cars comprising a housing adapted to be secured to

the lower bolster and provided with side and end retaining barriers and having a bottom, a wearing plate secured to said bottom and forming a bearing surface level from end to end, a roller in said housing free to roll on said bearing surface, and a spring member secured between said wearing plate and the bottom of the housing and having upwardly inclined end portions normally lying above the surface of said wearing plate.

20. In testimony whereof, I have hereunto set my hand.

ARNOLD STUCKI.
